United States Patent Office

Des. 182,703
Patented May 6, 1958

182,703

HANDLE FOR TRAYS OR SIMILAR ARTICLES

Ralph B. Billig, Westlake, and Manuel S. Ziskin, Mayfield Heights, Ohio, assignors to Kromex Corporation, Cleveland, Ohio, a corporation of Ohio

Application August 15, 1957, Serial No. 47,376

Term of patent 14 years

(Cl. D44—10)

FIG.2

Fig. 1 is a top plan view of a handle for trays or similar articles showing our new design; and

Fig. 2 is a front elevational view thereof.

We claim:

The ornamental design for a handle for trays or similar articles, as shown and described.
